N. AND F. WHITESEL.

STRETCHER.

APPLICATION FILED JUNE 17, 1918.

1,304,006.

Patented May 20, 1919.

UNITED STATES PATENT OFFICE.

NEWTON WHITESEL AND FREDERICK WHITESEL, OF OMAHA, NEBRASKA.

STRETCHER.

1,304,006.

Specification of Letters Patent. Patented May 20, 1919.

Application filed June 17, 1918. Serial No. 240,340.

To all whom it may concern:

Be it known that we, NEWTON WHITESEL and FREDERICK WHITESEL, citizens of the United States, residing at Omaha, in the 5 county of Douglas and State of Nebraska, have invented certain new and useful Improvements in Stretchers, of which the following is a specification, reference being had to the accompanying drawings.

10 This invention relates to certain improvements in stretchers and has relation more particularly to a device of this general character especially designed and adapted for use in connection with woven fence fabric 15 and it is an object of the invention to provide a novel and improved device of this general character including means whereby the stretching or pulling mechanism may be effectively supported at different heights in 20 accordance with the requirements of practice.

It is also an object of the invention to provide a novel and improved device of this general character which is provided with 25 means for engaging a fence post or other stationary abutment when in operation whereby the pulling or stretching action is materially facilitated.

Another object of the invention is to provide 30 a novel and improved device of this general character including a winding drum operated through the medium of a worm and wherein a flexible member coacts with the drum and which flexible member has operatively connected therewith a clamping member for engagement with a wire fabric or other element to be stretched.

A still further object of the invention is to 35 provide a novel and improved stretcher which may be readily and conveniently operated by one person and which device maintains the fabric in stretched condition so that the person who operates the stretcher may also anchor the fabric to a fence post 40 or the like.

The invention consists in the details of 45 construction and in the combination and arrangement of the several parts of our improved stretcher whereby certain important 50 advantages are attained and the device rendered simpler, less expensive and otherwise more convenient and advantageous for use, as will be hereinafter more fully set forth.

55 The novel features of our invention will hereinafter be definitely claimed.

In order that our invention may be the better understood, we will now proceed to describe the same with reference to the accompanying drawings, wherein:

Figure 1 is a view in perspective illustrating a stretcher constructed in accordance with an embodiment of our invention, and in applied position;

Fig. 2 is a fragmentary view partly in 65 horizontal section and partly in top plan illustrating the winding drum and operating means therefor as herein included; and

Fig. 3 is a fragmentary view partly in 70 transverse section and partly in plan of the clamping member as herein included.

As disclosed in the accompanying drawings our improved device comprises two elongated members 1 in vertical spaced relation when the device is in operative position 75 and the forward portions of said members 1 are in convergence and have secured between their forward extremities a block 2. The block 2 is provided with the transversely disposed head 3 preferably crescent 80 shape so that said head may have effective contact with a fence post or the like.

The members 1 at predetermined points longitudinally thereof are connected by the bolts 4 for maintaining the same in predetermined relation. Overlying the inner faces of the members 1 adjacent the rear ends thereof are the plates 5 maintained in applied position through the medium of certain of the bolts 4 and said plates are of such 90 configuration as to have their forward end portions extending beyond the opposite sides of the members 1. The extended portions of the plates 5 are connected by the bolts 6 arranged in pairs and positioned between the 95 bolts of each pair is a bearing block 7. The blocks 7 rotatably support the shaft 8 provided with the worm 9 meshing with a worm gear 10 carried by an end portion of the drum 11. The drum 11 is rotated around 100 the removable pin 12 supported by the members 1 at a point rearwardly of the bolts 6.

An end portion of the shaft 8 is provided with a head 14 through which is slidably disposed the operating lever 15. The lever 105 15 is adapted to be manually operated to impart the desired rotation to the drum 11. It will be obvious that by use of the worm 9 and the coacting worm gear 10 the drum 11 will be locked against rotation when the 110 shaft 8 is not being rotated.

One of the members 1 rearwardly of the

drum 11 is provided with an opening 16 in alignment with an end portion of the longitudinally disposed slot 17 produced in the second member 1. Disposed through the slot 17 and the opening 16 is a bar 18. The lower end of the bar 18 is pointed as at 19 and adapted to penetrate the ground. The bar 18 immediately adjacent the inner end portion of the point 19 is provided with a supporting plate 20 which is adapted to rest upon the surface so that the bar 18 will be maintained in a vertical position when the device is in applied position. The bar 18 is also provided with a series of longitudinally spaced transverse openings 21 through which a removable pin 22 is adapted to be disposed for coaction with one of the members 1 so that the drum 11 may be maintained at different elevations in accordance with the occasions of practice.

23 denotes a brace rod having its upper end portion provided with a hook member 24 freely disposed through an opening 25 produced in the rear portion of the upper member 1 and the lower or opposite end portion of the rod 23 is provided with the laterally directed eye member 26 through which a stake 27 or the like is adapted to be directed. In practice the rod 23 extends laterally with reference to the members 1 and in a direction away from the lever 15 so that the device, when in applied position, will be effectively braced against lateral strain as imposed thereupon during a working operation. The connection of the rod 23 with the member 1 as afforded by the hook member 24 permits the rod 23 to be readily swung relative to the member 1 with which it is engaged so that said rod 23 may be employed effectively irrespectively of the various adjustments of the members 1 longitudinally of the bar 18.

Anchored to one of the bolts 4 in advance of the drum 11 is an end portion of a flexible member M which is disposed around a pulley 28 carried by a clamping member C. The member M has its opposite end portion operatively engaged with the drum 11 so that as the member M is wound around the drum 11 upon requisite rotation of the shaft 8 the desired pull will be imposed upon the clamp C to properly stretch the woven fence fabric W or the like with which the clamping member C may be engaged. By this means it will be perceived that after the proper pull or strain has been imposed upon the fabric W the operator may readily secure the fabric to the post P or the like as the coaction between the worm 9 and the gear 10 will prevent retrograde movement of the fabric W after being stretched.

As herein disclosed the clamping member C comprises an elongated flat strip or rigid member 29 having imposed thereupon a second member 30. The member 30 is coex-

tensive in length with the length of the member 29 and has its longitudinal margins provided with the flanges 31 extending toward the member 29. The members 29 and 30 are connected for relative movement by the bolts 32 whereby the fabric W may be readily and conveniently clamped between the members 29 and 30. As herein disclosed the pulley 28 is rotatably supported by an arm 33 extending laterally from the member 30 at a point substantially midway thereof.

From the foregoing description, it is thought to be obvious that a stretcher constructed in accordance with our invention is particularly well adapted for use by reason of the convenience and facility with which it may be assembled and operated and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as hereinafter claimed.

We claim:

1. A wire stretcher comprising two elongated members arranged in vertically spaced relation when in working position, the forward portions of said members being in convergence, a block secured between the forward ends of the members and provided with a transversely disposed head, pulling means supported by and between the members adjacent the rear ends thereof, a ground engaging support adjustably engaged with both of the members, the rear portion of the upper member being provided with an opening, and a rod provided with a hook member at one end insertible through an opening in the upper member, said rod serving as a lateral support, and having swinging movement relative to the member.

2. A wire stretcher comprising a pair of elongated members arranged in vertically spaced relation when in working position, the forward extremities of said members being provided with an abutting member, a drum rotatably supported by and between the members adjacent the rear extremities thereof, a pair of bolts connecting the members at each side thereof and adjacent the drum, a bearing supported between the bolts of each pair, a shaft supported by the bearings and operatively engaged with the drum, and means for rotating the shaft.

3. A wire stretcher comprising a pair of elongated members in vertically spaced relation when in working position, an abutting member secured to the forward extremities of said member, a winding drum rotatably supported by and between the rear end portions of the members, plates secured to said members adjacent the drum and ex-

tending beyond opposite sides of the members, bolts connecting the extended portions of the plates and arranged in pairs at opposite sides of the members, bearing blocks 5 mounted between the pairs of bolts, a shaft mounted in the bearing blocks and operatively connected with the drum, and means for rotating the shaft.

4. A wire stretcher comprising a pair of 10 elongated members arranged in spaced relation, the forward extremities of said members being provided with an abutting member, a drum rotatably supported by and between the members adjacent the rear extremities thereof, a pair of bolts connecting 15 the members at each side thereof and adjacent the drum, a bearing supported be-

tween the bolts of each pair, a shaft supported by the bearings and operatively engaged with the drum, and means for rotating the 20 shaft.

In testimony whereof we hereunto affix our signatures in the presence of witnesses.
